UNITED STATES PATENT OFFICE.

JOHN H. MANNING, OF NEW YORK, N. Y., ASSIGNOR TO CRANE COMPANY, OF CHICAGO, ILLINOIS, A CORPORATION OF ILLINOIS.

PIPE-FLANGING MACHINE.

1,076,134.

Specification of Letters Patent. Patented Oct. 21, 1913.

Application filed November 23, 1910. Serial No. 593,767.

To all whom it may concern:

Be it known that I, JOHN H. MANNING, a citizen of the United States, and a resident of the borough of Brooklyn, in the county of Kings, in the city and State of New York, United States of America, have invented certain new and useful Improvements in Pipe-Flanging Machines, of which the following is a specification.

10 My invention relates to pipe flanging machines and its object is to improve upon machines of this character and to provide a simple and efficient apparatus for forming flanges on the ends of pipe of wrought steel 15 or other metal.

I will describe my invention in the following specification and point out the novel features thereof in the appended claims.

Referring to the drawings, Figure 1 is a 20 sectional side elevation of a machine embodying my invention. Fig. 2 is an end elevation of a pipe rest, a detail of this machine, and Fig. 3 is another detail, a stop bracket. Fig. 4 is a plan view, and Fig. 5 25 an end elevation of my improved machine. In Fig. 6 I have shown a sectional end elevation of the machine, the section of this figure being taken on the line 6—6 of Fig. 1. Fig. 7 is a sectional end elevation through 30 the line 7—7 of Fig. 1 looking in the opposite direction. Fig. 8 is a cross-section through one of the forming molds. Fig. 9 shows certain parts of the apparatus and the end portion of a pipe in sectional elevation and on a somewhat enlarged scale in the relative positions they assume at the beginning of the operation. Figs. 10, 11, 12, 13 35 and 14 are views of similar parts in different relative positions and illustrate the operation of the machine.

Like characters of reference designate corresponding parts in all of the figures.

10 designates the base of the machine upon which its various parts are mounted. Secured to this base is a pipe rest 11 which comprises a stand in which are adjustably held a pair of rollers 12. This pipe rest itself may be moved longitudinally along the frame and secured thereto in desired 45 positions.

13 is a carriage slidably mounted upon the base 10, a portion of which forms a longitudinal track therefor. 14 is a piston rod which connects this carriage with a piston 50 within a cylinder 15. One end of this cyl-

inder is connected with the base of the machine. The piston and piston rod are arranged to be actuated by fluid pressure manually controlled. By means of this arrangement the carriage 13 and its associated parts 60 may be moved back and forth a limited amount along the tracks which are formed by the base 10. To the carriage 13 is bolted a stand or bracket 16. The upper portion of this bracket is formed to fit loosely under 65 a pipe and to extend up at either side of it. It is clearly shown in Fig. 3.

17 is a die or forming mold clamp which is rigidly secured to the carriage 13 or its base is an integral part thereof. This clamp 70 is made in two parts, a base and a cap, which are pivoted together at 18 and arranged to be tightened by a bolt and nut at 19.

20 designates a forming mold which is circular in form but cut diametrically into 75 a lower half which is held in the base of the mold clamp 17 and an upper half held in the cap of this clamp by means of set screws 21.

A rotary disk 22 on the end of a shaft 23 is supported in pedestal bearings 24, 25. 80 Between the disk and the pedestal bearing 24 is a plate 26 which is arranged to take up end thrust. The shaft 23 may be driven by any suitable power mechanism, as for example, by a belt 27 which is connected 85 with it through reduction gearing 28.

Across the face of the disk 22 is a housing 30 which forms a groove with undercut edges in which are supported a pair of slideable blocks 31, 31. Between these blocks is a 90 compression spring 32. These blocks may be forced toward each other against the action of the spring and their positions, relative to the axis of rotation, may be adjusted by means of set screws 33, 33. In 95 each of the blocks is supported a transverse cylindrical roller 34. The outside surfaces of these rollers are in alignment with each other and are at substantially right-angles to the axis of the shaft 23. A pin 35 projects from the face of one of the blocks near its inner end. On this pin is a permanent roller 36, the forward edge of which is chamfered or rounded as shown, and its rear edge is arranged to overlap the roller 100 34. On the other block is a similar pin 37 on which is a removable flaring roller 38 which extends over the face of the roller 34 in this block. During the process of flange-forming, this roller is removed and a 110

smaller roller 39 which extends back of roller 34 is preferably substituted therefor.

50 designates a pipe upon the end of which the flange is to be formed.

5 51 is a strap collar which fits tightly around the outside of the pipe. This strap is made in two parts fastened together by bolts and nuts 52, by means of which it may be securely affixed to the pipe. The first

10 part of the operation is to securely fasten this collar to the pipe with its edge which is away from the end of the pipe, at a desired distance from that end of the pipe which is to be formed into a flange. If the

15 pipe is of wrought steel or similar metal this end of it is then heated, after which it is so placed in the machine that its end projects through the forming die or mold, 20, and that the collar 51 abuts against the

20 face of the stop-bracket 16. The die or mold is made in halves and its clamp so constructed that it may be opened to facilitate this part of the operation. The clamp is now closed and the die tightened by means

25 of the bolt and nut at 19. The other part of the pipe will be supported on the pipe rest 11. All of the parts are so adjusted that the pipe will be held with its axis in alignment with the axis of the shaft 23 and

30 the parts will be in some such relative positions as those in which they are shown in Fig. 9. The operator now forces the carriage toward the rotating disk 22 and as the bracket 16 is in engagement with the collar

35 51 the pipe will move with it. Its heated end is then forced against the flaring roll 38 which bends it outward into some such form as that in which it is shown in Fig. 10. As soon as this is done the carriage

40 is drawn back away from the rotating disk, the roller 38 is removed, and the cylindrical roller 39 preferably substituted therefor. Fig. 11 shows the parts ready for the next step of the process of treatment. Again

45 the carriage and pipe are forced toward the rotating disk. This time all of the rolls 34, 34, 36 and 39 will act upon the pipe as shown in Fig. 12 and force its end against the forming mold. A flange of desired

50 shape and size will thus be formed. But in order to perfect the flange and to increase its strength the process is carried on further. The carriage is again withdrawn and the mold 20 is loosened so that the flanged end

55 of the pipe may be moved through the mold or die into some such position as that in which it is shown in Fig. 13. A bar or wedge 53 is then thrust between the collar 51 and the bracket 16, the mold is tightened,

60 and the carriage is again advanced toward the rollers in the rotating disk. The metal will now be crushed between the mold and the rollers into the position shown in Fig. 14. This will result in upsetting the metal

65 at the end of the pipe and at the angle be-

tween the pipe and the flange so as to increase its density and its strength. While the roller 39 is preferably substituted for the flaring roller 38 in order to balance the side pressure produced by the roller 36, the transverse rollers 34 are largely if not solely depended upon for upsetting the metal at the end of the pipe and the roller 36 may alone be relied upon to keep the inside diameter of the end of the pipe to size by preventing the metal from being forced inwardly. In this case it is only necessary to remove the roller 38 after the first step in the flanging process is completed. Before the pipe is taken out of the machine I prefer to run the carriage back enough to remove the pressure of the rollers, to loosen the mold and to remove the bar 53. Then the pipe is partially rotated so that the rear of the flange will come in contact with different portions of the mold than those against which it was formed, the mold is tightened and the carriage is again forced toward the rollers. Thus a finish pressure is applied which trues up the flange. By carefully setting the position of the collar 51 at the beginning of the operation the finished flange will be of the desired thickness and diameter. The spring 32 cushions the strain on the rollers 36, 38 and 39. In small pipes the roller 36 is dispensed with, but when it is used in conjunction with the roller 39 the pressures on these rollers is balanced and the spring allows them to move in toward the center of the disk when any roughness such as a seam on the inside of a pipe is first met. Such protuberance will be rolled down, however, during the process of flange-forming. It has been noted that the roller 36 overlaps one of the rollers 34 and that the roller 39 runs past the end of the other roller 34. By this construction the end of the pipe is left with a sharp clean edge.

When flanges are formed with this apparatus on the ends of pipes of some metals such as brass or copper it is not necessary to heat the metal.

It is only necessary, in order to carry out my invention, to impart a relative rotation between the pipe and the forming rollers. The roller which is used to flare the pipe is forced against the end thereof to perform its function. It is obviously immaterial whether the movement imparted to it for this purpose is longitudinal or radial. The collar 51 and the bracket 16 against which it abuts are provided for the purpose of insuring the longitudinal movement of the pipe with the carriage 13. The dies themselves may be used to perform this duty if it is desired.

The pipe flange formed by this process is extremely strong. It is also of sufficiently large diameter to make it very effective in

forming various kinds of pipe joints. The fiber of the metal is nowhere bent over at a smaller angle than a right-angle. The flange is formed of the integral end of the pipe without any of its portions being folded together and welded so that in all places its grain or fiber is continuous. At the corner of the flange the cross-section of the metal is about twice as thick as that of the pipe or of the flange proper. Moreover, at this point where the greatest strains come in use, the metal is upset and thereby condensed and strengthened.

By the term "mold" I have reference to any suitable tool or device for accomplishing the desired function and my invention is not unnecessarily limited to a circular mold or a tool of any specific form.

What I claim is—

1. A pipe flanging machine comprising a forming mold adapted to fit loosely about a pipe near the end thereof, a device for holding the pipe relative to the mold in two longitudinally different fixed positions, means for successively forcing the end of the pipe against the mold when the pipe is held in its different positions relative to the mold.

2. A pipe flanging machine comprising a forming mold adapted to fit loosely about a pipe near the end thereof, a device for holding the pipe relative to the mold in different longitudinal positions, a rotatable disk opposite the end of the pipe, means carried by said disk arranged to act upon the pipe to form a flange on the end thereof while held in one of its positions and then to upset the metal in the pipe while held in another of its positions, and means for moving the holding device toward and away from said rotary disk.

3. A pipe flanging machine comprising a rotary disk mounted in a stationary bearing, a carriage movable toward and away from said disk, mechanism for forcibly actuating the carriage, a forming mold supported by the carriage adapted to fit about a pipe, means for causing the pipe to move longitudinally with the carriage; and rollers mounted upon the disk arranged to form the end of the pipe against said mold when the carriage is forced toward said disk.

4. A pipe flanging machine comprising a rotary pipe forming device mounted in a stationary bearing, a carriage movable toward and away from said device, mechanism for actuating the carriage, a forming mold supported by the carriage adapted to fit about a pipe near the end thereof, and a holding device on the carriage arranged to hold the pipe relative to the mold in two longitudinally different fixed positions.

5. A pipe flanging machine comprising a rotary disk, mounted in a stationary bearing, a carriage movable toward and away from said disk, mechanism for actuating the car-

riage, a forming mold supported by the carriage adapted to fit about a pipe, means for causing the pipe to move longitudinally with the carriage and to hold the pipe relative to the mold in different longitudinal positions; and rollers mounted upon the disk arranged to form the end of the pipe against said mold and to upset the metal of the pipe.

6. A pipe flanging machine comprising a rotary disk mounted in a stationary bearing, a carriage movable toward and away from said disk, mechanism for actuating the carriage, a forming mold adapted to fit loosely about a pipe, a clamp upon the carriage for holding the mold, a collar adapted to be secured to the pipe, a stop bracket projecting from the carriage against which said collar may abut, and rollers mounted upon the disk arranged to flare the end of the pipe and to form it against said mold.

7. A pipe flanging machine comprising a rotary disk mounted in a stationary bearing, a carriage movable toward and away from said disk, mechanism for actuating the carriage, a forming mold adapted to fit loosely about a pipe near the end thereof, a clamp upon the carriage for holding the mold, a collar adapted to be secured to the pipe, a stop bracket projecting from the carriage against which said collar may abut, a bar arranged to be interposed between said stop bracket and the collars, and rollers mounted upon the disk arranged to flare the end of the pipe to form it against said mold and to upset the metal of the pipe.

8. A pipe flanging machine comprising a rotary disk, a carriage movable toward and away from said disk, mechanism for actuating the carriage, a two-part forming mold adapted to fit about a pipe near the end thereof, a clamp upon the carriage for holding the mold, additional means for causing the pipe to move longitudinally with the carriage; and rollers on said block arranged to act upon the end of the pipe.

9. A pipe flanging machine comprising a rotary disk, a carriage movable toward and away from said disk, mechanism for actuating the carriage, a two-part forming mold adapted to fit about a pipe near the end thereof, a clamp upon the carriage for holding the mold, additional means for causing the pipe to move longitudinally with the carriage, and for holding the pipe in different longitudinal positions relative to the mold, an adjustable pipe rest for holding the pipe in alignment with the axis of the disk, and rollers on said disk arranged to act upon the end of the pipe.

10. A pipe flanging machine comprising a forming mold adapted to fit about a pipe near the end thereof, a flaring roller having the angularity of its axis fixed relative to the axis of the pipe, a resilient support for said roller, mechanism for imparting a relative

- rotation between the pipe and the axis of said roller, and means for forcing the pipe and said roller toward each other to cause the roller to form the end of the pipe 5 against said mold.
11. A pipe flanging machine comprising a rotary disk, a carriage movable toward and away from said disk, mechanism for actuating the carriage, a radially slidable block upon the face of the disk, a spring acting to force the block outward, an adjusting screw for moving the block inward, and rollers on said block arranged to act upon the end of the pipe.
12. A pipe flanging machine comprising a rotary disk, a carriage movable toward and away from said disk, mechanism for actuating the carriage, a pair of radially slidable blocks upon the face of the disk, a compression spring between the blocks, means for adjusting the positions of said blocks, a transverse roller in each block having its rolling surface at substantially right-angles to the axis of the disk, pivots projecting from the face of said blocks, and rollers adapted to be placed upon said pivots and arranged with said transverse rollers to act upon the end of the pipe.
13. A pipe flanging machine comprising a rotary disk, a carriage movable toward and away from said disk, mechanism for actuating the carriage, a pair of radially slidable blocks upon the face of the disk, a compression spring between the blocks, a transverse cylindrical roller in each block having its rolling surface at substantially right-angles to the axis of the disk, and a longitudinal roller projecting from each block with its axis in alinement with the axis of the disk, one of said longitudinal rollers being arranged to overlap its adjacent transverse roller, and the other transverse roller arranged to overlap its adjacent longitudinal roller.
14. A pipe flanging machine comprising a rotary disk mounted in a stationary bearing, a carriage movable toward and away from said disk, mechanism for actuating the carriage, a two-part forming mold adapted to fit about a pipe near the end thereof, a clamp 45 upon the carriage for holding the mold, a roller carried by the disk for flaring the end of the pipe, and other rollers also carried by the disk for forming the flared end of the pipe against the mold.
15. A pipe flanging machine comprising a rotary disk, a carriage movable toward and away from said disk, mechanism for actuating the carriage, a radially slidable block upon the face of the disk, a spring 50 acting to force the block outward, an adjusting screw for moving the block inward, and a pivot projecting from the block, arranged to support rollers of unlike form adapted to sequentially operate on the end 60 of a pipe.
16. A pipe flanging machine comprising a rotary disk, a carriage movable toward and away from said disk, mechanism for actuating the carriage, a radially slidable block upon the face of the disk, a spring acting to force the block outward, an adjusting screw for moving the block inward, and a roller in said block having its rolling surface at substantially right angles to the axis of the disk, a pivot projecting from the face of the block, arranged to support rollers of unlike form adapted to sequentially operate on the end of a pipe. 70
17. A pipe flanging machine comprising a rotary disk, a carriage movable toward and away from said disk, mechanism for actuating the carriage, a pair of radially slidable blocks upon the face of the disk, a compression spring between the blocks, means for adjusting the positions of said blocks, a transverse roller in each block having its rolling surface at substantially right angles to the axis of the disk, pivots projecting from the face of said blocks, and rollers adapted to be placed upon said pivots and arranged with said transverse rollers to act upon the end of the pipe. 75
18. A pipe flanging machine comprising a rotary disk, a carriage movable toward and away from said disk, mechanism for actuating the carriage, a forming mold adapted to fit about a pipe near the end thereof, a clamp upon the carriage for holding the mold, additional means for causing the pipe to move longitudinally with the carriage; a pair of rollers carried by the disk, having rolling surfaces at substantially right-angles to the axis of the disk, and a pivot projecting from the disk, adapted to support a conical roller in position for flaring the end 90 of the pipe and to support another roller of cylindrical form in position to fit inside the pipe. 95
19. A pipe flanging machine comprising a rotary disk, a carriage movable toward and away from the disk, mechanism for actuating the carriage, a forming mold adapted to fit about a pipe near the end thereof, a clamp upon the carriage for holding the mold, additional means for causing the pipe to be moved longitudinally with the carriage; a radially slidable block upon the face of the disk, a spring acting to force the block outward, an adjusting screw for moving the block inward, a roller in said block having its rolling surface at substantially right-angles to the axis of the disk, and a pivot projecting from the face of the block, arranged to support other rollers adapted to sequentially operate on the end 100 of a pipe. 105
20. A pipe flanging machine comprising a rotary disk, a carriage movable toward and away from said disk, mechanism for actuating the carriage, a forming mold 110

adapted to fit about a pipe near the end thereof, a clamp upon the carriage for holding the mold, additional means for causing the pipe to move longitudinally with the carriage and for holding the pipe in different longitudinal positions relative to the mold, a pair of radially slidable blocks upon the face of the disk, a compression spring between the blocks, screws for adjusting the positions of said blocks, a transverse roller in each block, said rollers having rolling surfaces in alinement with each other and at right-angles to the axis of the disk, a pivot projecting from the face of each block, and a longitudinal roller on one of said pivots arranged to overlap its adjacent transverse roller, the other of said pivots being arranged to support a conical roller in position for flaring the end of a pipe, and to support a cylindrical roller in position to fit inside the pipe and the end of its adjacent transverse roller.

21. A pipe flanging machine comprising a forming mold or tool, means for holding the pipe relative to the mold in two longitudinally different fixed positions, a rotatable member and rollers mounted thereon for successively forcing the end of the pipe against the mold or tool when the pipe occupies the two aforesaid fixed positions.

22. A pipe flanging machine comprising a forming mold or tool, means for holding the pipe relative to the mold in two longitudinally different fixed positions, a rotat-

table disk opposite the end of the pipe, 35 means carried by said disk arranged to act upon the pipe to form a flange on the end thereof and to upset the metal in the pipe at the flange and means for moving the holding means toward and away from said disk.

23. A pipe flanging machine comprising a rotary disk, a carriage movable toward and away from said disk, mechanism for forcibly actuating the carriage, a two part 45 forming mold or tool adapted to fit about a pipe near the end thereof, a clamp upon the carriage for holding the mold, additional means for causing the pipe to move longitudinally with the carriage and for holding 50 the pipe relative to the mold in two longitudinally different fixed positions, an adjustable pipe rest for holding the pipe in alinement with the axis of the disk, a flaring roller removably mounted on said disk adapted to form a flange on the end of the pipe and a second roller radially mounted on said disk and adapted to upset the metal in the pipe at the flange when the flaring 55 roller is removed.

In testimony whereof I have signed my name to this specification in the presence of two subscribing witnesses.
